UNITED STATES PATENT OFFICE.

ALBERT INGELSKY, OF BUFFALO, NEW YORK.

DESIGN FOR A PLAQUE.

60,454.

Specification for Design. Patented Feb. 21, 1922.

Application filed April 22, 1921. Serial No. 463,642. Term of patent 3½ years.

To all whom it may concern:

Be it known that I, ALBERT INGELSKY, a citizen of the United States, residing at Buffalo, in the county of Erie and State of New York, have invented a new, original, and ornamental Design for a Plaque, of which the following is a specification, reference being had to the accompanying drawing, forming a part thereof.

The figure is a perspective view of a plaque embodying my new design.

The plaque shown in the accompanying figure and embodying my design, includes a panel or support A and a pin cushion B, a thermometer C, a calendar D, a memorandum pad E and match box F, and a pencil G mounted thereon, as shown.

I claim:

The ornamental design for a plaque as shown and described.

Buffalo, New York, April 9, 1921.

ALBERT INGELSKY.
